UNITED STATES PATENT OFFICE

ARTHUR HERSCHDORFER AND GEORGE ASNESS, OF NEW YORK, N. Y.

COMBINED SPRAYING AND POLISHING MACHINE

Application filed May 12, 1926. Serial No. 108,473.

This invention relates to improvements in combined spraying and polishing machines, and has particular reference to a machine of this character especially adapted for use in spraying and polishing metal surfaces such as the surfaces of signs, doors, walls and the like.

An object of the invention is to provide a practical machine which will be effective in facilitating the application of a polishing liquid to a surface and in polishing said surface after the liquid has been applied.

Another object is to draw, by suction, the liquid to be sprayed from a reservoir and feed said liquid to a nozzle where it is atomized by the current of air utilized to draw the liquid from said reservoir.

Another object is to provide a common source of power for agitating the liquid in the reservoir and for controlling the feed of said liquid from the reservoir to the spray nozzle.

A further object is to provide spraying and polishing units which may be interchangeably connected to a common source of power utilized to control the operation thereof.

A still further object is the provision of a polishing roller, the effective surface of which is yieldingly supported in such manner that the same will readily conform to the contour of flat or curved surfaces to which said roller may be applied.

The above and other objects will appear more clearly from the following detail description, when taken in connection with the accompanying drawings, which illustrate preferred embodiments of the inventive idea.

In the drawings—

Figure 1 is a longitudinal section through the machine showing the spraying head as engaged on the apparatus;

Figure 1A is a similar sectional view of the polishing unit;

Figure 2 is a similar view through the spraying unit employed in connection with the invention;

Figure 3 is a horizontal section of the spraying unit illustrating parts thereof in plan view;

Figure 4 is a vertical sectional view

through the nozzle device of the spraying unit;

Figure 5 is an enlarged sectional view of a part of the nozzle device;

Figure 6 is a transverse sectional view through the polishing unit, illustrating parts thereof in front elevation;

Figure 7 is a longitudinal section through one form of polishing roller;

Figure 8 is an end elevation of said roller;

Figure 9 is a view similar to Figure 7 illustrating another form of roller; and

Figure 10 is a longitudinal section through still another form of polishing device showing the manner of its attachment to the shaft of an operating motor.

Referring more particularly to the drawings, the numeral 1 indicates an electric motor of any desired type which furnishes the power for operating the various units constituting the parts of the invention. This motor is provided with a drive shaft 2 which extends through the front wall 2^a of a casing 3 enclosing the motor 1. This casing has secured thereto the arms 4 and 5 to which is attached a handle 6 fastened in position by a bolt 7 extending through the handle and extremities of the arms 4 and 5.

The spraying unit, which is adapted to be attached to the casing 3 and connected to the shaft 2 of the motor in a manner presently to appear, consists of a casing 8 having a rear wall 8^a and an extension 8^b projecting from said rear wall which fits over the front portion of the casing 3 with the rear wall in abutting relation to the front wall 2^a of the latter casing. In order to secure the casing 8 in position the wall 8^a thereof is provided with rearwardly projecting hook members 51 which extend through slots 8^c formed in the wall 2^a. A sliding latch member 51^a is vertically mounted in the forward end of the casing 3 and provided at its upper end with a push rod 52 normally projected outwardly through the top of the casing 8 by means of a leaf spring 53. The latching member 51^a is provided with slots 54 through which the hook members 51 project and when said latching member is in its normal position with the hooks as shown in Figure 1, the casing 8 will

be locked in position on the casing 3. By pressing the rod 52 downwardly it will be apparent that the latching member may be disengaged from the hooks 51 and thus permit of the detachment of the casing 8 from the casing 3.

When the two casings are in the position described the shaft 2 projects into the hub 9 of a worm gear 10, which hub is secured to the wall 8^a and rotatably supports said worm gear. A portion of the shaft 2 may be square or said shaft may be provided with a keyway so that rotation will impart a similar movement to the worm 10. Meshing with the worm 10 is a gear 11 secured to a shaft 12 suitably supported by the wall 8^a above the hub 9 and this shaft also has fixed thereto a disk 13 utilized to operate the pitman 14 connected to one end of the piston rod 15. The other end of the rod 15 carries a piston 16 mounted for reciprocation in the cylinder 17 of an air pump suitably secured to the front wall of the casing 8. The cylinder 17 is provided adjacent each end thereof with flap valve controlled air inlet ports 18 and 19 which alternately admit air into the cylinder as the piston 16 is reciprocated. The cylinder 17 is also provided with flap valve controlled outlet ports 20 and 21 for permitting the escape of pressure from the cylinder into the outlet pipes 22 and 23, respectively, the two pipes being joined together, as shown in Figures 3 and 4. The pipe 23 terminates in a header 24 disposed within the upper end of a hood 47. This header is provided with depending air nozzles 37, 38, 39 and 40 through which passes the current of air created by the pump.

A liquid reservoir 25 is mounted upon the bottom of the casing 8 and is provided with a cover 30 having a flange 48 extending partly around the same, which flange projects into a groove 49 in the top of the wall of the reservoir. A suitable substance may be placed in the groove 49 to seal the cover of the reservoir and thereby aid in making the latter liquid tight. The cover may also be secured in position by screws 50. Extending from the reservoir 25 to the header 24 is a feed pipe consisting of a section 26 rotatably connected, as at 27, to the section 28 secured in the top 30 of the reservoir and having a curved extension 29. This extension 29 is coupled to a plurality of branches 31, 32, 33 and 34 constituting a part of the feed pipe, said branches diverging from the extension 29 and having their outer ends extending into the header 24. The section 26 of the feed pipe is rotatably mounted so that its outer free end will always be immersed in the liquid in the reservoir regardless of the position in which the machine may be tilted while working with the same. Thus if the front end of the machine is inclined downwardly the weight of the section 26

would cause the same to swing to a position diametrically opposed to that shown in Figure 2 and would thereby remain immersed in the liquid. The ends of the branches 31, 32, 33 and 34, which extend into the header 24, are provided with liquid nozzles 36, the outer ends of which are so disposed with respect to the adjacent air nozzles that when the current of air entering the header 24 passes through the latter nozzles a suction will be created in the nozzles 36 which will be sufficient to draw the liquid from the reservoir 25 outwardly into the various branches and to the nozzles 36 where said liquid will be atomized into the form of a spray and be projected outwardly against a surface by said current of air.

It may be desirable to agitate the liquid in the reservoir 25 and for this purpose there is provided a gear 43 meshing with the worm gear 10 and carried by the upper end of a shaft 45 journaled in a bearing 44 supported by the wall 8^a of the casing. The shaft extends downwardly into the reservoir 25 and carries an agitator element 46 at the lower end thereof which is constantly rotated so as to continuously agitate the liquid in the reservoir while the machine is in operation.

After the spraying operation, should it be desired to use the polishing unit shown in Figures 1A and 6, the spraying unit is detached by depressing the rod 52 to release the hooks 51 from the latching member 51^a whereupon the casing 8 may be detached and the casing 41 of the polishing unit thereupon attached to the casing 3 in the same manner as described in connection with the casing 8. The polishing unit includes a bearing member or sleeve 42 which is adapted to fit over the projecting end of the shaft 2 of the motor 1 and surrounded by the ball bearings 68 held in place by means of a collar 67. The sleeve 42 carries a bevel gear 55 which meshes with a similar gear 56 fixed to the shaft 56^a. The ends of this shaft are rotatably supported in bearings 56^b suitably attached to the rear wall of the casing 41 and one end of said shaft carries a spur gear 57 which meshes with a similar gear 58. The latter gear is supported intermediate the ends of one of the two supporting arms 60, the rear ends of which are pivotally connected in any suitable manner to the rear wall of the casing 41.

A larger gear 59 meshes with the gear 58 and is provided with a stub shaft 69 which projects through the forward end of the adjacent arm 60, while the opposite arm 60 carries another stub shaft 69 similar to the first named stub shaft. The forward ends of the arms 60 are supported by a hanger 61 from which extend the plunger rods 62 each mounted for movement within a tubular member 63 pivotally connected at 98 to the top of the casing 41. Interposed between the upper end

of each tubular member and the adjacent end of the plunger 62 is a coil spring 64 which normally exerts a downward pressure upon the plunger 62 so as to force the hanger 61 in a downward direction. In order that the plungers 62 will be maintained within the tubular members said plungers are provided with pins 65 projecting into longitudinal slots 66 formed in said members 63. The hanger 61 supports a polishing roller, generally indicated by the numeral 70, by mounting said roller upon the stub shafts 69. Thus when the roller is in position the same will engage a surface to be polished and will be yieldingly held in such engagement by the springs 64. While the roller is thus supported it will be apparent that the same will have movements relative to the casing 41 by reason of the pivotal connection of the arms 60 and members 63 with the casing 41, it being understood that the lower free ends of the side arms of the hanger 61 are also pivotally connected to the arms 60, as indicated at 70a.

In the form of roller illustrated in Figures 7 and 8, the same is shown as including a body portion consisting of an outer cylindrical layer 71 of felt or any other suitable polishing material and an inner cylindrical member 72, which is preferably made of rubber. By thus constituting the body portion it will be apparent that the same has imparted thereto a degree of flexibility which will permit the effective surface of the roller to conform to the contour of flat or rounded surfaces so that the entire area of the surfaces may be engaged by the roller. The body portion of the roller is supported in concentric relation with the axis of rotation thereof by means of a plurality of leaf springs 73, the outer ends of which engage the inner surface of the member 72 while the inner ends of said springs are secured in any preferred manner to the periphery of the core 74 of the roller. In each end of the core 74 there is mounted a bearing 75 normally forced outwardly by a coil spring 76 and having its outward movement limited by a stop 76a engaging the bearing member. A portion of each bearing member is square so that when said member is rotated a similar movement will be imparted to the roller. The outer end of each bearing member is provided with a socket 77 for receiving the free end of an adjacent stub shaft 69 upon which the roller is supported. Thus when the motor 1 is operated rotation will be imparted to the roller 70 through the train of gearing including the gears 55, 56, 57, 58 and 59.

The body portion of the roller including the members 71 and 72 may be made to assume the form shown in Figure 9, due to the elasticity of the member 72, by utilizing a plurality of springs 73 arranged at intervals about the core 74, the central springs being of shorter length than the other springs so

that the central portion of the roller will assume a constricted position and thus produce a longitudinal curvature in the body portion of the roller. The roller is further supported by a plurality of disks 78 of different diameters arranged about the core 74, said disks being preferably made of relatively stiff rubber. The disks have their peripheries beveled to conform to the curvature of the adjacent portion of the member 72 of the body portion and said disks are movable longitudinally of the core in accordance with the pressure upon the polishing surface of the roller, the longitudinal movements of said disks being controlled to some extent by the interposition of the coil springs 79 between said disks which yieldingly maintain the latter substantially equidistances apart. It will be understood that a roller of this type is particularly adapted for use in polishing corrugated surfaces.

In Figure 10 there is shown another form of polishing device which is adapted for attachment directly to the shaft 2. When this form of the device is used the casing 41 is dispensed with. The device shown in Figure 10 includes a shank 82 terminating at its outer end in a conical head 83. The shank 82 carries a spring pressed latch 81 one end of which projects through an opening 80 in the shank and engages in a recess 82a formed in the end of the shaft 2 upon which the device is mounted, thus locking the device to said shaft. The head 83 is covered by an inner member 84 of rubber and an outer member 85 of felt, the latter providing the polishing medium which may be engaged in relatively deep recesses in surfaces to be polished, which recesses cannot be reached with the forms of rollers shown in Figures 7 and 9.

What is claimed is:

1. A portable spraying apparatus comprising a casing enclosing a motor having an extending shaft, a second casing containing a closed tank, means for removably engaging said casings to form a rigid unit, a multiple spray head, an air pump in the second casing driven by said motor shaft, and means including a pivotally mounted suction head actuated by said pump to extract liquid from said tank and force the same through said spray head.

2. A portable spraying apparatus comprising a casing containing a closed circular tank, a reciprocating air pump, a header to receive air from said pump, a plurality of jets connected with said header, a hood to direct effluent from said jets, a gravity rotatable suction device in said tank to reach its lowermost part irrespective of angular position, branches from said device associated with said jets to deliver liquid thereto, and means for actuating said pump.

3. A portable spraying apparatus comprising a casing containing a closed tank, a

reciprocating air pump, a header to receive air from said pump, a plurality of jets connected with said header to deliver outwardly of the casing, a hollow arm entering the tank axially, branches connecting said arm and jets, means to actuate said pump, a rotatable fan combined with said actuating means to agitate the contents of said tank, and an intake member pivotally mounted on said arm to swing by gravity in said tank to the lowermost portion thereof automatically upon movement of the casing.

4. A portable spraying apparatus comprising a cylindrical liquid reservoir, a nozzle, an automatic feed pipe movable by gravity on the axis of the reservoir and communicating with said nozzle, means for discharging a current of air through said nozzle to create a suction therein to draw the liquid from said reservoir and atomize the same at said nozzle, and a rotary element for agitating the liquid in said reservoir while it is being fed from said feed pipe.

5. A hand conveyed spraying apparatus comprising a circular liquid reservoir, a nozzle, a feed pipe connecting the reservoir with said nozzle and including sections one of which is rotatably connected to the other end disposed axially within said reservoir, means for discharging a current of air through said nozzle to create a suction therein to draw the liquid from said reservoir and atomize the same at said nozzle, rotatable paddle means for agitating the liquid in said reservoir while it is being drawn through said feed pipe, and a common source of power for operating said discharging and agitating means.

6. A hand conveyed spraying apparatus comprising a casing, a liquid reservoir in said casing, a plurality of air nozzles supported by said casing, a plurality of liquid nozzles each arranged in juxtaposition to one of said air nozzles, an air pump in said casing, connections between said pump and air nozzles for conveying a current of air through said nozzles to create a suction in said liquid nozzles, gravity operable, revolvable connections between the latter nozzles and said reservoir through which the liquid in the reservoir is conveyed by said suction to said liquid nozzles and there atomized by said current of air, and means for operating said air pump.

7. A portable spraying apparatus comprising a cylindrical casing, a liquid reservoir in said casing, a plurality of air nozzles supported by said casing, a plurality of liquid nozzles each arranged in juxtaposition to one of said air nozzles, an air pump in said casing, connections between said pump and air nozzles for conveying a current of air through said nozzles to create a suction in said liquid nozzles, connections between the latter nozzles and said reservoir,

said connections comprising an hollow arm downwardly inclined at its end, mounted to swing on the axle of said reservoir, and through which the liquid in the reservoir is conveyed by said suction to said liquid nozzles and there atomized by said current of air irrespective of the angular position of the reservoir, means for operating said air pump, and a rotary agitator in said reservoir also operated by the last named means.

In testimony whereof we have affixed our signatures.

ARTHUR HERSCHDORFER.
GEORGE ASNESS.
